UNITED STATES PATENT OFFICE.

ADDISON C. PHILPOTT, OF BUCYRUS, OHIO.

ELECTRIC SWITCH.

1,176,984.

Specification of Letters Patent. Patented Mar. 28, 1916.

Application filed January 8, 1914. Serial No. 811,113.

To all whom it may concern:

Be it known that I, ADDISON C. PHILPOTT, a citizen of the United States, residing at Bucyrus, Crawford county, and State of Ohio, have invented and discovered certain new and useful Improvements in Electric Switches, of which the following is a specification.

My invention relates to electric switches and its object is to provide means of a simple and effective character for enabling a switch member to be alternately moved in opposite directions by successive energizations of a magnet whereby, if desired, current may be directed alternately through different circuits, and specifically to provide mechanical means for so positioning the switch moving means that the said opposite successive movements of the switch member will be effected by the movement of the magnet armature in one direction.

With these ends and others in view, my invention is embodied in preferable form in the device hereinafter described and illustrated in the accompanying drawings.

In these drawings, Figure 1 is a front view in elevation of a switch and the magnet showing the switch blade in contact with a fixed contact member and showing the armature drawn down by the energization of the magnet; Fig. 2, a front view in elevation showing the switch blade in contact with the same fixed member as in Fig. 1, but showing the magnet deenergized and with the blade moving member in position to shift the switch blade in the opposite direction upon the reenergization of the magnet; Fig. 3, a view similar to Fig. 1, showing the switch blade in contact with the right hand contact member and with the magnet energized; Fig. 4, a front view in elevation showing the switch blade in the position indicated in Fig. 3, but with the magnet deenergized and Fig. 5, a vertical section at right angles to Fig. 1.

Referring to the drawings, 1 is a magnet of the solenoid type having a core or armature 2, to the upper end of which is pivoted an arm 3, which carries at its upper end a cross arm 4. The arms 3 and 4 constitute a switch blade operating member and this member is capable of a lateral swinging movement on the pivot connecting the same with the core of the solenoid.

Mounted on a pivot pin 5, extending into a suitable support, is a switch blade 6 which

is adapted to establish a circuit through either fixed contact member 7 or fixed contact member 8, the said switch blade being laterally shiftable from one contact member to another to establish different circuits or to make and break one circuit. The pivot pin 5 and the contact members 7 and 8 are adapted to be connected by wires 9, 10 and 11 to a suitable source of electrical energy. The pin 5 is spaced from the arm 3 and the pin and the contact members 7 and 8 are mounted upon a suitable support from which they are separated by suitable insulating material. The switch blade is provided at its lower end with a tilting cross arm 12, which carries at each end thereof an outwardly projecting pin or stud 13. Such pins are made of non-conducting material. These pins are adapted to be engaged by notches 14-14 formed in the lower edge of the arm 4 of the switch blade actuating member and also by notches 15-15 provided in said arm and extending more deeply into the surface thereof than the notches 14. The notches 14 constitute means of connection between the shifting member and the blade for moving said blade while the notches 15 constitute guiding and guarding recesses and serve to permit the descent of the blade shifting member when carried downwardly by the magnet core and to also prevent said member from being shifted laterally beyond the said pins.

Connected to an arm 16 extending laterally from the vertical arm 3 of the switch blade operating member is a spiral spring 17, the other end of which is connected to a fixed support. This spring serves as the means for carrying the switch blade operating member into position to shift the switch blade in a direction opposite to that in which it has been carried by the energization of the solenoid. This member performs its positioning function when the solenoid is deenergized.

The operation of the device is as follows:

In Fig. 1 the solenoid has been energized, the core pulled down and the switch actuating member also pulled down and it will be seen that as a result of this action, the left hand notch 14 of the switch blade operating member has engaged one of the pins 13 on the cross arm of the switch blade and has carried said pin downwardly rocking the switch blade on its pivot, so as to

carry the latter into contact with the left hand contact member. The other pin on the opposite end of the cross arm of the switch blade has been carried into engagement with 5 the deep notch 15 at the corresponding end of the operating member. The parts will remain in this position with a circuit established through the switch blade and the left hand contact member until the solenoid is 10 deenergized. When this action takes place, the spring 17 will carry the switch blade operating member, consisting of the arms 3 and 4 upwardly and such member in such upward movement will assume the true vertical position and in moving to such position the right hand notch 14 on the upper arm 4 will be carried over into alinement with and above the right hand pin 13 of the tilted arm of the switch blade, said switch blade 15 and its arm remaining in the position shown in Fig. 1. The position resulting from the action thus described is indicated in Fig. 2 from which it will appear that the right hand notch 14 of the switch blade operating 20 member is in engagement with the right hand pin of the switch blade, ready to depress the right hand end of the switch blade cross bar when the operating member and the solenoid core are again pulled downwardly 25 by the energization of the solenoid. Upon such reenergization of the solenoid, the operating member will accordingly tilt the right hand of the cross bar of the switch blade downwardly, thus shifting the switch blade 30 from the left hand contact member over into engagement with the other member to establish a new circuit or break the first circuit, and the parts will assume the position shown in Fig. 3 until the current through 35 the solenoid is broken, whereupon they will take the position shown in Fig. 4, owing to the retractive action of the spring, and will 40

then be in position to effect the reshifting to the arrangement in Fig. 1. It will be seen by this arrangement that the switch blade 45 may be shifted in opposite directions by successive movements of the solenoid core in the same direction and that this action is effected by mechanical means supplemental to the electrical operating means provided by the 50 solenoid.

Having thus described my invention, what I claim is:

In an electric switch, in combination with a fixed contact member, a swinging pivoted 55 blade, a solenoid, an armature, a swinging member movable in a plane parallel to the plane of movement of said switch blade and pivoted to said armature below the pivot of said switch blade, said tilting member having a cross arm extending to each side of the pivot of said member and having two pin engaging slots at each end of said cross arm, one of said slots being deeper than the other, said switch blade having a cross arm 60 extending substantially parallel to the cross arm of the tilting member and having a pin at each end thereof adapted to engage said slots and a spring connected to said tilting member and operable to restore the same to vertical upright position when the solenoid is deenergized whereby the said member will be shifted alternately into positions for moving the switch blade in opposite directions in successive movements of the latter. 70

In witness whereof, I have hereunto set my hand and seal at Indianapolis, Marion county, Indiana, this third day of January, A. D. nineteen hundred and fourteen.

ADDISON C. PHILPOTT. [L.S.]
